TAPE MOISTENING DEVICE FOR MAIL
TREATING MACHINES

Commodore D. Ryan and Edward P. Drake, Los Angeles, Calif., assignors to Commercial Controls Corporation, Rochester, N. Y., a corporation of Delaware

Original application December 11, 1940, Serial No. 369,570. Divided and this application January 19, 1945, Serial No. 573,513

11 Claims. (Cl. 101—232)

1

This invention relates broadly to mail treating machines, and more particularly to apparatus incorporated in such a machine for feeding and moistening gummed tape on which a postage value has been printed.

An object of the invention is to provide a hand operated printing machine of the type referred to which is particularly rapid and reliable in operation, and relatively simple and rugged in construction. Another object is to provide a relatively simple and effective machine for printing postage or the like on a tape fed from a roll of tape in the machine and discharged from the machine after being printed. A still further object is to provide apparatus of the above nature by which the printed tape may be moistened and delivered for application as desired. Another object is to provide in a machine of the above character tape moistening mechanism which is automatically conditioned for operation when the mail treating machine is set to print on tape. Other objects will be in part apparent and in part pointed out hereinafter.

This application is a division of our copending application Serial No. 369,570, filed December 11, 1940, entitled "Printing machine" which is issued as Patent 2,380,331 on July 10, 1945.

The invention accordingly consists in the features of construction, combinations of elements and arrangements of parts as will be exemplified in the structure to be hereinafter described and the scope of the application of which will be indicated in the following claims.

The manner in which the foregoing objects and features of the invention are accomplished, together with other features and objects, will be explained by describing in detail a particular embodiment of the invention as disclosed in the drawing.

In the drawing:

Figure 1 is a perspective view of the machine; Figure 1A is a horizontal view through a machine in accordance with the invention, as viewed partly in plan and partly in section, with portions of the upper cover broken away and showing the construction therebelow;

Figure 2 is a vertical section taken substantially in the plane 2—2 of Figure 1A;

Figure 3 is a sectional skeleton view of certain parts taken substantially in the vertical plane 3—3 of Figure 1A;

Figure 4 is a skeleton view similar to Figure 3, but showing some of the parts in a different position;

2

Figure 5 is a detail vertical section taken substantially in the plane 5—5 of Figure 1A;

Figure 6 is a vertical skeleton view, taken substantially along the line 6—6 of Figure 1A;

5 Figure 7 is a detail developed section, taken along the curved line 7—7 of Figure 5;

Figure 8 is a section taken in the same plane as Figure 6, but showing some of the parts in different positions;

10 Figure 9 is a developed section similar to Figure 7 with the parts in the same position as shown in Figure 8;

Figure 10 is still another section, similar to Figure 5, but showing the parts in still another 15 position of operation;

Figure 11 is a developed section, similar to Figures 7 and 9, but showing the parts in the same position of operation as they occupy in Figure 10;

20 Figure 12 is a detail vertical section taken in the plane 12—12 of Figure 10;

Figure 13 is a detail horizontal section taken in the plane 13—13 of Figure 10;

25 Figure 14 is a skeleton view taken substantially in the vertical plane 14—14 of Figure 1A; and,

Figure 15 is a detail section, taken in a plane parallel to the section of Figure 14, but showing the moistening device and associated elements 30 in section.

Referring first to Figures 1 and 1A, the machine of the present invention comprises a frame formed largely of sheet metal sections and including a bottom horizontal base plate 1 to which 35 are fastened upwardly extending wall plates 2, 3, 4, and 5. The front wall member 2 which extends across one end of the machine is formed continuous with side wall members 6 and 7. The sides of the machine are further enclosed by wall 40 portions 9 of a suitable cover.

Secured to the top of the wall members 3 and 4, and supported thereby, is a horizontal mounting plate 10 for supporting a postage printing machine 11. This machine 11 may be of the 45 type described in the copending application of Frank P. Sager, Ernest R. Bergmark, Commodore D. Ryan and Herschel L. Atherton, Serial No. 332,305, filed April 29, 1940, for Mail treating machine. The details of the postage printing machine 11 do not constitute a part of the present 50 invention. Suffice it to say that the postage meter includes a rotary printing head 60 (Figure 8) which is rotated to carry a printing face 61 thereon first past an inking roller 62, and then into 55 contact with such mail matter as is passing

through the machine, i. e. envelope or tape. Thus, as the leading edge of the printing face 61 moves into contact with the mail matter, the latter is supported by a rotary platen 64 (Figure 1A) which rotary platen rotates in synchronism with but in opposite direction to the printing head to carry the mail matter between the printing head and platen exactly as it would be carried through the rolls of a clothes wringer.

This platen 64 is mounted upon the shaft 59 to which the main crank 58 is secured and is directly rotated thereby. It is preferably made of yieldable material such as rubber, and is of arcuate extent substantially equivalent to the arcuate extent of the printing face 61 on the printing head 60.

Crank 58 includes a handle 59 which when revolved causes printing drum 60 (Figure 14) and platen 64 to revolve so that mail matter is fed therethrough by frictional engagement between the printing face 61 and platen 64. This movement of the envelope delivers its leading edge between a discharge roller 122 (Figure 1A) and an idler roller 123 which is supported for rocking movement toward and away from the roller 122 on arms 124 (Figure 3) that are pivotally supported on a shaft 125. The discharge roller 122 is rotated rapidly to frictionally engage and discharge the envelope after it is released from the printing face and platen.

The roller 123 is urged toward the roller 122 by gravity and also by the action of a torsion spring 127 (Figure 1A). One end of the torsion spring 127 is anchored to a stationary collar 128 on the shaft 125 and the shaft in turn is supported against rotation on an arm 130, which arm is pivotally mounted on the shaft 65 by a universal bearing 160a and is normally maintained in the position shown in Figure 6. The other end of the spring bears against a connecting plate 132 which interconnects the arms 124 which support the roller 123.

The construction and operation of the machine for printing directly on envelopes or other such objects fed through the machine is described in detail in the above-noted copending application of which this is a division. As previously indicated, the machine is also equipped to print postage on a strip of gummed tape, which tape can then be stuck to mailing matter. This feature is particularly useful for attaching postage to objects of such size or shape that they cannot be fed through the machine.

To adapt the machine for printing and delivering tape, a tape-handling mechanism 200 (Figure 2) is swung into position to feed tape between the printing head and the platen (Figure 8).

The discharge mechanism including the roller 122 and the roller 123 are not necessary when printing tape and would be in the way. Hence when the machine is adjusted to print postage on tape, this discharge roller assembly is swung downwardly out of the way by the operation of rotating a control handle 201 (Figure 1) in counterclockwise direction through an angle of approximately 120°. The handle 201 is secured to the end of a shaft 202 which is journaled in the two wall members 2 and 3 (Figure 12). This initial rotation of the shaft 202 is transmitted through a ball clutch mechanism 203, to be described later, to a sleeve 204 rotatable on the shaft 202. The sleeve 204 has secured thereto an arm 205 (Figure 6) which has pivotally connected thereto, as by a pivot screw 206, the lower end of a link 207, the upper end of which is piv-

totally connected by a screw 208 to the arm 130 on which the rollers 122 and 123 are mounted. When the handle 201 is in its lower position, as shown in Figure 1, the sleeve 204 is oriented as shown in Figure 6, and the arm 205 extends almost vertically, holding the arm 130 in its upper position for the discharge of envelopes. Clockwise rotation of the sleeve 204 is limited by the fact that as the pivot screw 206 moves clockwise (with reference to Figure 6), slightly past dead center position, a lip 205a on the arm 205 engages against the link 207 and prevents further movement.

The over-center position of the arm 205 makes the mechanism irreversible; i. e., it is impossible to rotate the arm 205 by force applied to the arm 130. It will be apparent from inspection of Figure 6 that the counter-clockwise rotation of the sleeve 204 and arm 205 through substantially 120° lowers the right end of the arm 130 and the rollers 122 and 123, as shown in the two views of Figures 3 and 4, respectively. It will also be apparent from Figure 4 that the rollers not only swing about the shaft 65 on which the arm 130 is pivotally supported, but also about the bearing 148, this movement being permitted by the fact that both the bearings 160a and 148 are of the universal type.

Movement of the handle 201 as described for shifting the discharge rollers out of the way, also functions to rock the tape-handling mechanism 200 from the inactive position shown in Figure 5 into the active position shown in Figure 8, this movement also being effected by rotation of the sleeve 204.

A mechanism is provided for cutting off the printed section of tape discharged from the tape feeding mechanism at the completion of the cycle, this mechanism being described in detail in our copending application Serial No. 531,346, filed April 17, 1944.

It should be noted here, however, that the tape cutting mechanism 250 is mounted at the delivery or forward end of the tape chute, the tape passing through the shearing mechanism as it leaves the chute to be severed for removal from the machine. Thus the tape mechanism is carried by the tape at the forward end thereof and participates in movement of the chute to and from its operative position relative to the nip between the printing drum 60 and platen 64.

When the tape cutting mechanism 250 is in the position shown in Figure 8, the tape feeds thereunder and out over a deflecting shelf 271. Shelf 271 (see Figure 15) is constituted by the base of a yoke member having flanged portions 272 which are pivotally supported on pins 273 into the side members of the tape handling mechanism. A tension spring 274, stretched between a pin 275 on one of the flanges 272 and a pin 276 on the corresponding side frame of the tape handling mechanism normally maintains the shelf 271 in the position shown in Figure 8, in which one of the flanges rests against a stop pin 277. Positioned immediately above the shelf 271 is a cross pin 279 supported between the extended side members of the tape handling mechanism, and the tape feeds between the shelf 271 and the pin 279 when the shelf and pin are in the Figure 8 position.

The shelf 271 is slightly curved to direct the tape upwardly so that it may be easily grasped and removed from the machine after printing and cutting off. The pin 279 is located centrally between the edges of the shelf and is positioned

so that the bottom side of the pin is about flush or even a little below the upturned edges of the shelf 271, so that as the tape is projected between the pin 279 and the curved shelf 271, it will curve upwardly. Due to the fact that the fibers in the tape have been oppositely stressed by winding on the roll, the tape has a tendency to bend in the opposite direction to that of the curved shelf 271. Thus the tape is frictionally held between the pin 279 and shelf 271, after cutting, until removed.

The machine is adapted to deliver the gummed tape in either dry or moistened condition. When the tape is to be delivered dry, it is discharged directly from the machine after passing over the shelf 271 as previously described. On the other hand, when the tape is to be delivered from the machine in moistened condition, it is delivered from the shelf 271 cutting off mechanism through a moistening device now to be described.

Referring to Figures 14 and 15, the moistening device comprises a water pot 315 having a brush 316 which is supported by a brush holder 317 positioned in the lower part of the pot, the brush extending upwardly from the holder 317 and out of an aperture provided therefor in the top wall 318 of the water pot. A portion of the top wall 318 is extended downwardly alongside the brush to form a baffle 319 to prevent water being splashed out through the brush aperture when the pot is swung into and out of moistening position, as will be described later. The pot is provided with a filler tube 320 which extends down into the pot from a filler opening adapted to be closed by a swinging lid 321. The tube 320 functions to prevent splashing of the water out through the filler opening when the pot is swung. The pot is equipped with a guide plate 322 spaced above the top portion 323 of the pot, to define a chute for guiding the tape across the brush 316. Water rises through the brush by capillary action to keep the upper portion of the brush sufficiently wet to properly moisten the tape as the latter feeds across the brush.

When the pot 315 is swung into the tape-moistening position shown in Figure 15, the pot engages against an arm 271a on the shelf 271 pivotally mounted at the exit end of the cutting off mechanism, and rocks the shelf forwardly and downwardly from its Figure 8 position to its Figure 15 position to bring the outer edge 271b of the shelf against the top wall 323 (Figure 15) of the pot, to direct the tape to the brush.

To support the water pot, a movable pot holder is provided, this holder consisting of a partial cylindrical wall member 324 formed integrally with a bottom plate 326. Plates 325 and 326 are apertured to receive a stationary supporting post 327 which is supported on the bottom plate of the machine. The upper plate 326 is extended to form a supporting shelf upon which the water pot sets and has an upward extension 328 which is received within a slot defined by a strap member 329 secured to one side of the water pot. It will be apparent that the water pot can be placed on or removed from the holder by simply sliding it onto or off of the extension 328.

When out of use, the moistening device is swung from the position shown in Figure 14, downwardly and forwardly into the position shown in Figure 1A, in which it is out of the way of the discharge roller and below the envelope supporting table.

The pot holder is slideable vertically on the post 327 and is supported vertically by a pin 330 extending radially from the post, which pin projects into a helical slot 331 in the cylindrical wall mem-

ber 324 so that the holder and the pot thereon is raised or lowered in response to rotation of the holder on the post 327. As shown in Figure 11, the lower end of the helical slot 331 is provided with a detent notch 332 to receive the pin 330 and maintain the pot in uppermost position after it has been moved into that position. The detent notch 332 provides sufficient resistance to rotation of the pot to prevent the latter from rotating in response to the frictional drag of the moving tape against the brush.

A mechanism is provided for rotating the pot holder to swing it into and out of tape moistening position, in response to actuation of the handle 201. Thus the bottom plate 325 of the holder is provided with gear teeth 333 constituting a gear segment which meshes with a rack 334 formed on one edge of a link member 335, which link member has a slot 336 through which extends the post member 327. The post 327 has slidably mounted thereon a spool-shaped bushing 337 which has a hub section slidably fitting in the slot 336, and lower and upper flanges which engage the under side of the link member 335 and the upper side of the bottom plate 325, respectively, to maintain the rack 334 in mesh with the segment 333 during the vertical movement of the mechanism on the post 327.

The link 335 is pivotally connected at its left end (with reference to Figure 11) to the upper end of an arm 339, which arm is secured to a hub 340 rotatable on the shaft 202 (Figure 12).

A ball clutch mechanism is provided for selectively coupling the shaft 202 to the arm 339 during a portion of its movement, and to the sleeve 204 during another portion of its movement. Arm 339 is more particularly described in connection with the mechanism for shifting the tape delivering mechanism into and out of operating position in our copending application, Serial No. 369,570, filed December 11, 1940. This ball clutch mechanism is so arranged that during counterclockwise rocking of the handle 201 from the position indicated in broken lines in Figure 2, through about 120°, into the position indicated in broken lines in Figure 8, the shaft 202 is coupled to the sleeve 204 so that the latter is rocked to swing the tape handling mechanism from the inactive position into the active position and simultaneously shift the discharge roller mechanism from active position into inactive position, all as shown in Figure 8. The mechanism is so arranged that if the handle 201 is then rocked an additional distance counterclockwise into the position shown in broken lines in Figure 11, the shaft 202 is uncoupled from the sleeve 204 and is coupled to the arm 339 so as to shift the water pot from inactive to active position. It should be noted that it is possible to swing the water pot into active position only after the discharge roller mechanism has been swung into inactive position, as may be observed from inspection of Figures 3 and 4.

The ball clutch mechanism comprises an arm member 341 pinned to the shaft 202 and having parallel end faces which abut against the arm 339 and against a flange 342 on the end of sleeve 204, respectively. The arm member 341 has a hole 343 therein of diameter to contain a pair of balls 344. It will be observed from inspection of Figure 12 that the thickness of the arm 341 is less than twice the diameter of the balls 344, so that they cannot be completely contained within the hole 343 but must protrude from one end or the other 75 of the hole.

With the handle 201 in the position shown in broken lines in Figure 2, with the tape moving mechanism in inactive position, and with the water pot in inactive position, the parts of the ball clutch occupy the relative positions shown in Figure 7, in which it will be observed that the arm member 341 rests against a flat portion of the arm 339 and is juxtaposed to a recess 342a in the flange 342 so that the flange 342 is constrained to rock with the arm 341. This condition prevails during rocking movement of the arm 341 until the handle 201 reaches the intermediate position indicated in broken lines in Figure 8, at which time the hole 343 in the arm 341 moves into registration with a recess 339a in the arm 339, as indicated in Figure 9. At this time the tape handling mechanism has been moved into active position and further movement of the sleeve 204 is prevented. Therefore when the handle 201 is rocked further counterclockwise from the position shown in Figure 8 into the position shown in Figure 10, the upper ball (Figure 9) is forced out of the recess 342a and the lower ball is simultaneously forced into the recess 339a so that the further movement of the arm 341 shifts the arm 339, as shown in Figure 11. This rocks the arm 339 to shift the water pot from inactive to active position.

To facilitate proper operation of the ball clutch mechanism, as described, the arm 339 is provided with an arcuate surface 345 concentric with the shaft 202 and having a pair of recesses 346 and 347 which receive a spring-pressed ball detent 348, when the water pot is in its two positions of operation. Thus, when the water pot is in active position, the detent 348 is in the recess 347 which tends to retain the mechanism in the position shown. On the other hand, when the handle 201 is in the intermediate position shown in Figure 8, then the ball detent 348 is in the recess 346 and properly centers the arm 339 while the water pot is in inactive position. The detent mechanism is desirable because there is substantial lost motion in the gear rack and segment connection to the water pot, and the limiting positions of the pot mechanism alone do not accurately fix the limit positions of the arm 339. It is desirable that the limit positions of the arm 339 be accurately fixed in order to insure proper operation of the ball clutch mechanism.

It is to be understood that although for the purpose of explaining the invention a particular embodiment thereof has been described in considerable detail, many variations from the exact construction disclosed will occur to those skilled in the art, and the invention is to be limited only as set forth in the appended claims.

We claim:

1. A printing machine comprising a printing head and platen operable to print on and feed objects therebetween, a tape-supporting and feeding mechanism movable between an inoperative position clear of said printing head and platen and an operative position adjacent the contacting surfaces of the printing head and platen, moistening means for moistening tape discharged from said printing head and platen, said moistening means being movable into operative and inoperative positions, a control member movable between first, second and third positions, and means coupling said control member to said tape supporting means and said moistening means for moving said tape supporting means into operative position while leaving said moistening device in inoperative position in response to movement of said control member between first and second positions, and

for moving said moistening device from inoperative to operative position while leaving said tape supporting means in operative position in response to movement of said control member from 5 second to third position.

2. A tape treating machine comprising a chute for guidingly supporting a gummed tape, means for treating and feeding tape through said chute, moistening means for moistening tape discharged 10 from said chute, and means supporting said moistening means for movement into and out of operative relation with said chute, comprising a vertical post, a member slidably and rotatable on said post for supporting said moistening means, cooperating means on said supporting member and post guiding said member for simultaneous twisting and vertical movement on said post, whereby said moistening device is supported for movement in a helical path extending 15 downwardly and away from said tape chute, and means for yieldably restraining said supporting means in its upper extreme position.

3. A tape treating machine comprising a chute for guidingly supporting a gummed tape, means 20 for treating and feeding tape through said chute, moistening means for moistening tape discharged from said chute, and means supporting said moistening means for movement into and out of operative relation with said chute, comprising hinge 25 means revolvably supporting said supporting means for swinging movement from a position in operative relation with said chute to a position clear of the path of tape discharged from said chute, and means for yieldably restraining said 30 moistening means in operative and inoperative positions.

4. A tape treating machine comprising a chute for guidingly supporting a gummed tape, means 35 for treating and feeding tape through said chute, moistening means for moistening tape discharged from said chute, means supporting said moistening means for movement into and out of operative relation with said chute, a shelf for guiding tape issuing from said chute, means supporting 40 the shelf for rocking movement between a first position in which it directs tape in a first direction and a second position in which it directs tape in a second direction, means yieldably urging said shelf into said first position, and co- 45 operating means on said shelf and said moistening means for shifting said shelf into said second position in response to movement of said moistening means into operative position.

5. Apparatus as described in claim 2, including 50 gear means on said supporting member, rack means adapted to mesh with said gear means, means for mutually supporting said rack means and gear means in meshing relation while permitting longitudinal motion of said rack means 55 to rotate said gear means, control means movable between two positions, and means responsive to movement of said control means for shifting said rack means longitudinally.

6. Apparatus as described in claim 2, including 60 gear means on said supporting member, rack means adapted to mesh with said gear means, means for mutually supporting said rack means and gear means in meshing relation while permitting longitudinal motion of said rack means to rotate said gear means, control means movable 65 between two positions, means responsive to movement of said control means for shifting said rack means longitudinally, said means for shifting said rack means comprising an arm oscillatable upwardly and laterally, and a longitudinal 70

extension on said rack means pivotally connected to said arm, horizontal movement of said arm in such direction as to raise the gear means being accompanied by simultaneous upward movement of the arm, whereby said rack means is maintained substantially normal to the axis of said gear means during actuation thereof.

7. A printing machine comprising, in combination, a rotatable printing head, a cooperating rotatable platen, means for rotating said printing head and platen, means for supporting and feeding a tape between said printing head and platen, means for moving said tape supporting means into and out of operative relation with said printing head and platen, a tape moistening device, means mounting said tape moistening device for spiral movement into and out of operative relationship with said printing head and platen so that when in operative position said moistening device may receive printed tape from between said printing head and platen, and control means connected to said tape supporting means and to said moistening device for moving said tape supporting means and said tape moistening means into and out of operative position, said control means comprising a single manually operable member which upon operation first moves said tape supporting means into operative position and thereafter moves said tape moistening means into operative position.

8. A printing machine comprising, in combination, a rotatable printing head, a cooperating rotatable platen, means for rotating said printing head and platen, means for supporting and feeding a tape between said printing head and platen, means for moving said tape supporting means into and out of operative relation with said printing head and platen, a tape moistening device, means pivotally mounting said tape moistening device for pivotal movement into and out of operative relationship with said printing head and platen so that when in operative position said moistening device may receive printed tape from between said printing head and platen, and control means connected to said tape supporting means and to said moistening device for moving said tape supporting means and said tape moistening means into and out of operative position, the pivotal axis of said tape moistening means extending at right angles to the axis of rotation of said platen.

9. A printing machine comprising, in combination, a rotatable printing head, a cooperating rotatable platen, means for rotating said printing head and platen, means for supporting and feeding a tape between said printing head and platen, means for moving said tape supporting means into and out of operative relation with said printing head and platen, a tape moistening device, means pivotally mounting said tape moistening

device for pivotal movement into and out of operative relationship with said printing head and platen so that when in operative position said moistening device may receive printed tape from between said printing head and platen, and control means connected to said tape supporting means and to said moistening device for moving said tape supporting means and said tape moistening means into and out of operative position, said means which mounts the tape moistening means for pivotal movement into and out of operative position including cooperating elements which upon the pivotal movement of the tape moistening means into operative position raise the tape moistening means to a position wherein the moistening portion thereof lies adjacent the delivery end of the tape feeding means.

10. A printing machine comprising, in combination, a rotatable printing head, a cooperating rotatable platen, means for rotating said printing head and platen, means for guiding an object to be printed upon between said printing head and platen, means for engaging and discharging objects after passage thereof between said printing head and platen, means for supporting and feeding a tape between said printing head and platen, means for moving said discharge means from an operative position adjacent said platen and printing head into an inoperative position displaced therefrom, means for moving said tape supporting means into and out of operative relation with said printing head and platen, tape moistening means and means supporting it for movement between operative and inoperative positions, said moistening means and said object discharging means being located in substantially the same position when in their operative positions, control means for moving said tape supporting mechanism into and out of operative position, and means also responsive to said control means for moving said discharging means from said operative to said inoperative position and thereafter moving said moistening means from inoperative into operative position.

11. A tape treating machine comprising, in combination, a chute for guiding and supporting a gummed tape, means for treating and feeding tape through said chute, moistening means for moistening tape discharged from said chute, means mounting said tape moistening device for spiral movement into and out of operative relationship with respect to the delivery end of said chute, whereby when said moistening means is in operative position it can receive and moisten tape discharged from the delivery end of said chute, and means operatively connected to said tape moistening device for moving said device into and out of its operative positions.

COMMODORE D. RYAN.
EDWARD P. DRAKE.
